[57] CLAIM

The ornamental design for a combined toothpick and dental floss holder, substantially as shown.

DESCRIPTION

FIG. 1 is a side elevation of a combined toothpick and dental floss holder showing my new design;

FIG. 2 is a bottom plan view thereof;

FIG. 3 is a top plan view thereof;

FIG. 4 is an elevational view thereof taken from the end at the left of FIG. 1; and

FIG. 5 is an elevational view thereof taken from the end at the right of FIG. 1.
